UNITED STATES PATENT OFFICE.

SEXTUS A. EDDINS, OF BROCKTON, AND WILLIAM H. BAYNARD, OF BOSTON, MASSACHUSETTS.

ART OF MAKING LOW-CUT SHOES.

1,386,850.

Specification of Letters Patent.

Patented Aug. 9, 1921.

Original application filed August 29, 1919, Serial No. 320,686. Divided and this application filed November 28, 1919. Serial No. 341,086.

To all whom it may concern:

Be it known that we, SEXTUS A. EDDINS, a citizen of the United States, and resident of Brockton, in the county of Plymouth and State of Massachusetts, and WILLIAM H. BAYNARD, a citizen of the United States, and resident of Boston, in the county of Suffolk and State of Massachusetts, have invented an Improvement in the Art of 10 Making Low-Cut Shoes, of which the following description, in connection with the accompanying drawings, is a specification, like letters on the drawings representing like parts.

15 Our invention is an improved process for making low cut shoes, oxfords, pumps, and the like, and is a division of our prior application, Ser. No. 320,686, filed August 29, 1919, describing both the process and the 20 improved last used therewith.

As explained in our said prior application, considerable difficulty has been heretofore experienced in the manufacture of so-called low cut boots, shoes, pumps, oxfords, 25 slippers, etc., during the pulling over and lasting action. In making low cut shoes it has been impossible to hold the upper materials snugly or firmly onto the last to resist the pull and strain of the lasting operation, because of the length of the shoe 30 opening. In high cut shoes, where lacing or buttons hold the upper materials on the last, the same difficulty is not experienced, as when making shoes without such laced or 35 buttoned top. It has, therefore, been the practice to apply tacks through the upper or through the lining or even to secure to low cut shoes an extra strip which was tacked directly to the last to hold the edge 40 of the upper in alinement with the style, design and fit intended, and then to last the shoe. Such prior operations, however, have been most unsatisfactory, have necessitated repeated and continuous handling, requiring 45 hand operations and resulting in inaccuracy in the tacking, unevenness in the strain, damages to the shoe, and poor fitting in the resulting oxford, pump or low cut shoe. Our invention contemplates the novel 50 process of temporarily securing the edge of the upper to the last along a substantial line and to effect this securing action with-

out injury to the upper material, entirely independently of any tacking, holding strips or similar devices, and yet to enable 55 the upper to be quickly alined, clamped and held, and instantly released when the last is completed. Our improved last and clamping arrangement is intended to be 60 claimed in said prior application and in the present case we have elected to claim the improvement in the art or process of making low cut shoes by means of a temporary clamping apparatus secured to a last or by 65 means of the last itself considered as an article of manufacture with the clamping devices thereon. We believe that the feature of thus holding the upper in low cut shoes, oxfords, pumps and the like, in alinement with the design and style of shoe, and along 70 a substantial length, to resist the lasting strain, protect the upper and maintain it uninjured, thus insuring even lasting, fitting and stretching of the leather while holding 75 the upper materials in correct and desired alinement in shape, constitutes an improved method and we wish to claim the same broadly.

Referring to the drawings illustrating our improved last, novel type of clamp, and 80 showing the process of lasting—

Figure 1 is a perspective view of one type of clamp which may be employed;

Fig. 2 is a side view of a pump shoe on the last with the clamping holding same in 85 position; and

Fig. 3 is a cross sectional view on the line 3—3 of Fig. 1.

The drawings illustrate our process as applied to the usual type of welt made shoe, 90 but it is of equal importance, as will be explained later, in the manufacture of turn shoes.

It will be appreciated that the last and clamp shown in the drawings are for purposes of illustration only and that our invention, broadly considered, is not limited to this type of last or clamp—any last and suitable clamping devices being within the scope of the invention and intended to be 95 covered by certain of the appended claims. The improved process of making such shoes, is the same irrespective of the type of last or style and design of clamp employed.

Referring to the drawings, a last 1 is illustrated in conventional form; on which shoe upper materials 2 are assembled, such shoe being of the low cut, oxford, or pump type. A sole or insole 3 is also illustrated, such shoes being either of the turn, welt, or McKay type—usually turns, or welts—and therefore as illustrated in the drawing, 3 indicates an insole. With the insole and 10 upper thus assembled, the upper materials are lasted, *i. e.*, pulled over and the marginal edge of the insole around the forepart and shank and secured thereto by lasting tacks driven partly into the insole 3 and last, as 15 indicated at 4, 4. It is this lasting action on such a type of pumps which has been so difficult heretofore to perform, the topmost edge of the upper materials 5 being substantially unsupported from the throat of the 20 vamp 6 to the heel 7. When lasting a laced or buttoned shoe, the upper materials are held across the top of cone of the last and thereby resist the pull of the lasting operation but in the type of shoe herein considered, the 25 edge 5 has no means to hold against the last without additional attachment to the last. Our invention contemplates the use of attachable and detachable clamping devices, quickly operable, to engage and hold the 30 edge 5 of the upper materials on each side of the last, at a substantial width, without injuring the upper and independently of the manual tacking operations, etc., above briefly explained. Such a clamp may be 35 temporarily or permanently secured to the last 1 and preferably is quickly operable by any suitable mechanical means.

The drawing illustrates a simple form of our clamp and to fit the same to the last 1 a recess 10 is bored through the cone of the 40 last at a sufficient height to be above the edge 5 of the upper materials of a shoe intended to be made thereon. Through this recess 10 the clamp may be fitted comprising, as here shown, a sleeve 12 internally threaded to receive correspondingly threaded bolt 14, the latter having a head 15 with a beveled face 16 adapted to bear against a clamp plate 17. The sleeve 12 carries a 45 handle 18, also having its inner surface formed as a beveled face 19 to bear against the clamping plate 20. Partial rotation of the handle 18 acts to lengthen or to shorten the combined bolt formed by the members 50 12 and 14 and thereby to tighten or release the clamps 17 and 20 against the sides of the last 1 or against the marginal portion 5 of the upper materials 2 on said last.

In operation, a clamping apparatus may 60 be attached to each last and the upper and insole assembled thereon, the edge portion 5 of the upper on each side of the last being fitted under the clamp 17 and 20 while the latter are loose on the members 12 or 14 in 65 extended position. The upper can thus be

aligned properly on the last and usually a tack 21 applied to the heel. Thereupon a handle 18 is manipulated to clamp the sides of the upper firmly on the last, whereupon it is ready for the side lasting operation, 70 driving of the tacks 4 and completion of the shoe. If desired, the clamp may be entirely detached from the last and applied to another last, and, if desired, the shoe upper may first be applied to the last and then the 75 clamp fitted thereto to clamp and hold the upper. While we have illustrated our type of clamp to include the right and left hand threaded arrangement shown in the members 12 and 13, we contemplate the use of 80 any other mechanically equivalent means such as cams to quickly tighten and loosen the clamps 12 and 20—also to form these clamps of such length and contour as may best carry out the invention on particular 85 lasts or goods.

In the making of turn shoes of the low-cut type, the sole is applied to the last with the tread surface next the last surface, and the upper applied thereon inside out. The 90 shoe is then lasted, and sewed, and the last withdrawn and the shoe turned. Thereupon the shoe now turned is relasted, and in this operation a last having our improved clamp, should be employed to carry out the process 95 on turn shoes. At the time of relasting such low cut shoe of the turn type it has heretofore been necessary to pull upwardly the edge portion of the top of the upper materials and tack the same to the last, whereas 100 by our process we are enabled to pull up the upper snugly along the last, after relasting, and then clamp the same thereto, thus saving marring by lasting tacks, and eliminating all the objectionable tacking operations, 105 as already explained.

Our invention is further described and defined in the form of claims as follows:

1. The improved process of making low cut shoes which consists in assembling the 110 upper materials on the last, pulling over the toe portion, and clamping the topmost portion of the upper tightly along the sides of the last for a substantial length between the throat of the vamp and the heel to hold the edge of the upper in alignment during the lasting operation.

2. The improved method of making low cut shoes which comprises assembling the upper materials on the last, clamping a substantial length of the marginal edge of the upper tightly against the last and on both sides of that portion of the last lying between the throat of the vamp and the heel, then lasting the shoe, then disengaging the 120 upper from the last and completing the shoe.

3. That improvement in the art of making shoes wherein a lacing or button upper is not employed, which consists in assembling the upper materials and sole or insole 130

on the last, preliminarily fitting the upper, temporarily securing the topmost edge portion of the upper to the last on each side thereof, without perforating the upper, per-
5 forming the lasting, and then completing the shoe.

In testimony whereof, we have signed our

names to this specification, in the presence of two subscribing witnesses.

SEXTUS A. EDDINS.

WILLIAM H. BAYNARD.
